UNITED STATES PATENT OFFICE.

SAMUEL E. CREASEY, OF SANFORD, MAINE.

GAME APPARATUS.

No. 887,464.

Specification of Letters Patent.

Patented May 12, 1908.

Application filed April 10, 1907. Serial No. 367,459.

To all whom it may concern:

Be it known that I, SAMUEL E. CREASEY, a citizen of the United States, residing in Sanford, county of York, and State of Maine, have invented an Improvement in Game Apparatus, of which the following description, in connection with the accompanying drawing, is a specification, like letters on the drawing representing like parts.

10 This invention has for its object the production of a game apparatus capable of being used for amusement under different conditions, as, for instance, with a board laid out substantially as illustrated and with movable objects traversing the several paths laid out thereon. The apparatus may be used to play a game that I will designate Noah's Ark, and with slightly different movable objects and slight variations in rules or order of moving, a game may be played which may be designated "horse racing", "boat racing", or a game portraying boys running in races either singly or in teams.

15 The chief characteristics of the device are a series of starting points, a series of paths or roadways divided into sections, a section for each starting point, and a goal to be reached by movable objects traversing certain paths, the endmost space of each section of the innermost path leading to a goal.

20 Herein I have chosen to illustrate my invention as designed for playing the game designated "Noah's Ark".

Figure 1 represents the face of the board; Fig. 2 a side elevation thereof; Fig. 3 one of the movable objects, such as I intend to employ in the game; Fig. 4 is a top plan view of a different moving object which I designate as a hoodoo; Fig. 5 is an enlarged section in the line x' , Fig. 1. Fig. 6 is a perspective view of two ordinary dice used in playing the game.

Referring to the drawings, A represents a board laid out in spaces having three paths or roadways, B, C, D, D representing the innermost or short path or roadway, and E representing a revoluble portion having a hollow button e that is rotatably mounted upon a stud e' sustained by the board, the revoluble portion having an opening or gate e^2 , said portion being shown as made in a plurality of colors, the portions e^3 , e^4 , and e^5 being of one color, and with the opening e^2 , separating the revoluble portion into the four spaces corre-

sponding in color with the starting points F, G, H, M, said spaces, like the said starting points, being of different colors.

The roadway or path is made up in sections of three spaces to a section, and opposite each starting point is a crossway leading from the starting point to the central revoluble portion without crossing the individual spaces of any section. Each crossway is provided with several spots of the same color as the color designating the starting point, and a spot of the same color is provided at the endmost space of each of the four sections of the innermost path or roadway D. For instance, referring to the starting point F, f represents a spot of the same color, and the arrow gives the direction of move in which a piece or moving object designated by the same color is to start on its journey, and having traversed the outermost path B to the position f' the moving object then follows the direction of the arrow and enters the first section of the roadway or path C, and having traversed that roadway or path and arriving at f'' the movable object follows the direction of the arrow and enters the first space of one of the sections of the innermost path or roadway D, and said moving object must be made to traverse entirely about said innermost path or roadway to the point f^3 from which point under the rules of the game as hereinafter laid out, the movable object may demand that the revoluble central portion E be turned to bring the gate or open part e^2 opposite said object to uncover a portion 20 designated as a goal, there being four such goals displayed on the portion of the board underneath the revoluble portion E.

The movable objects tagged to designate the particular color of the point from which they started, will be moved as described for the object starting from the point F, and in the drawing, I have indicated the line of movement of the objects leaving the starting point G by g , g' , g^2 , g^3 ; the moving directions of the objects starting from H by the letters h , h' , h^2 , h^3 , and as herein illustrated, the goal is open opposite the endmost space of that one of the sections that defines the extent of movement of the movable object leaving the starting space H; and so also the moving positions and directions of the objects starting from space M are designated m , m' , m^2 , and the final position of said object as m^3 , from

which point it must if possible enter the goal.

It will be understood that there may be four players, one for each starting point, and each starting point has a distinctive color.

During the game the moving objects may change from one to another owner, and in the starting of the game a certain number of the objects are chosen, and to indicate to which particular space and consequently which particular person playing the game any individual moving object belongs, I have combined with each object a tagging device *p* herein shown as a disk having four spots differing in color, the colors corresponding with the colors of the starting points so that by revolving the tag any of the four colors may be placed at the rear of the object to display its ownership, and when in the rules of the game an object may be captured by an opponent, the opponent has only to revolve the tag and place his particular color at the rear of the object.

In playing Noah's Ark I have chosen to stand an image *r* representing Noah in a slot in the pedestal *r'* carried by the revoluble center *E*.

I will now briefly describe how to play the game which I have designated Noah's Ark. This game is simple enough for children, and yet presents to older players many problems of strategy which eliminates the idea of chance.

Referring to the board the circular spaces at the corners are the starting points, each having as stated a different color and the objects leaving the starting points must traverse one after the other the eccentric paths or roadways on the board and the animals must come together during this travel two by two before entering the goal or being entitled to occupy a position on the central space *E* which may be designated the ark.

When playing the game of Noah's Ark the movable objects are provided in pairs and suitably weighted so that they may stand easily after being moved from one to another space in each of the various sections comprising the several paths or roadways.

50   Rules.

1. The game may be played by two, three, or four players.

2. Each player is assigned one corner of the board as a starting point, on which are placed several animals, no two of which are of the same kind. If there are to be two players, there must be two, three, or four animals at each starting point; if three players, then two or four animals; and if four players, two or three animals. The number of animals is to be chosen according to the length of time intended to be spent in the play, as a greater number of animals makes a longer game. The color disk attached to

each animal is turned so that the spot of the same color as the starting point is placed directly behind the animal. Throughout the progress of the game, ownership of any animal in play is shown by the color of the spot directly behind it, which will always be of the same color as its owner's starting point. A separate animal called the hoodoo is placed in the center of the board.

3. All the players then throw the dice for the lead, the player throwing the highest total number of spots taking the lead.

4. After the play has begun, the player first throwing a single five, draws the hoodoo, which he places on his starting point with his animals, having arranged its color disk as in rule 2.

5. Each successive player throwing a single five must enter one of his animals or his hoodoo in the outer circle in the square directly in front of his starting point, indicated by arrow No. 1. Not more than two animals may stand on the entering space at one time, except that the hoodoo may stand with two animals. This rule for the number of animals on a space also applies to any space in the circles.

6. The animals are then advanced to the right in the outer circle as many spaces as the total number of spots on either one die at the player's last throw. Each throw of doublets entitles the player to an extra turn. This applies also in rules 4 and 5.

7. A pair may be mated, if one overtakes the other on the same space, the holder of the animal overtaken losing it. The new owner of the pair, who is the holder of the animal overtaking the other, must change the disk attached to the animal just taken to his own color as in rule 2. If the disk is not so changed before the next move of the player holding the pair, he shall forfeit ownership of the pair to the player from whom he took the mate, provided that the latter calls attention to the fact of not so changing the disk. A mated pair is moved as one animal, both animals being picked up and moved together.

8. An animal or pair having come from the left to the space directly in front of its owner's starting point must be entered in the next inner circle and only in the direction indicated by the arrow.

9. A pair having arrived in the inmost circle shall enter the ark, or central space, by the gateway directly in front of its owner's starting point.

10. A pair can enter the ark only by a throw of the dice corresponding exactly with the number of spaces required to enter, the dark green space in the open gateway counting as one of the required spaces. The progress of the pair must always be to the right.

11. If a player should reach the entrance with an unmated animal, he shall continue moving it about the inmost circle, in order

that it may come up with its mate, if possible, as only mated pairs can enter the ark.

12. Mated pairs having arrived at the entrance to the ark but not permitted by rule 5 to enter must not again go around the inmost circle but must remain at the entrance until permitted by the rules to enter.

13. A player holding the hoodoo shall not enter any pair into the ark while he holds the 10 hoodoo.

14. The hoodoo may be moved in any direction and from any circle to any other by any passage most convenient, *i. e.* its freedom of motion is limited only by the number of 15 spots of the dice thrown as in the case of the other animals. It shall not enter the ark.

15. When the hoodoo comes on a space occupied by a single animal or mated pair, the holder of the hoodoo must exchange it 20 for the single animal or mated pair. When the exchange takes place, the disks must be changed immediately to show the holder's color. If the new owner of the animals fails so to change the color disks before making 25 his next move and the holder of the hoodoo calls attention to the fact by calling "hoodoo", an exchange back must be made.

16. If the hoodoo comes on a space occupied by two unmated animals, it is not exchanged for either but may stand with both on the same space.

17. If the hoodoo is on a space with a single animal and the mate of this animal comes on the same space, the holder of the pair thus 35 mated must immediately exchange it for the hoodoo. The color disks must be changed as in other exchanges of animals.

18. A player may try to gain the hoodoo, always, however, moving to the right, if by 40 so possessing the hoodoo he may gain an advantage later.

19. A player losing all the animals in his possession becomes out of the game.

20. The game continues until no animals 45 are left out of the ark except the hoodoo and the animals in the possession of its holder. The player having entered the largest number of pairs wins.

50 *The Progressive Game of Noah's Ark.*

If a number of players are gathered for an evening party, much enjoyment may be derived from a progressive game. The plan is similar to other progressive games.

55 It is preferable that the four at each table play as partners, each couple having a certain number of counters, such as small disks or rings.

Each couple winning shall take as many 60 counters from the losers as they have entered pairs of animals into the ark, and shall advance to the next table.

The couple losing at the head table shall go to the foot table at the end of every game.

65 The couple holding the largest number of

counters at the end of the evening or period of play shall be the winners, and may receive a small favor or prize.

Having fully described my invention, what I claim as new and desire to secure by Letters Patent is:—

1. A game apparatus comprising a board provided with a plurality of starting points, a series of roadways inclosed by said starting point, each roadway comprising a series of 75 sections, each section being divided into a number of spaces, a series of goals located practically at the center of the board, a revolute section having an open gate to cover all but one of said goals, a crossway leading from 80 each starting point to the revolute section having the gate, each goal being located opposite the endmost space of each section of the innermost path or roadway.

2. A game apparatus comprising a board 85 having starting points differing in color, a series of concentric paths or roadways laid out in sections, each section displaying a plurality of spaces, a central portion having a series of goals, a crossway leading from each of 90 the starting points between the endmost spaces of the different sections comprising the roadway, each of said crossways having a series of spots of a color corresponding to the color of the nearest goal to indicate the paths 95 to be taken by moving objects to the endmost space of that one of the sections of the innermost path or roadway from which the moving object must be moved to enter the goal.

3. A game apparatus comprising a board having starting points differing in color, a series of concentric paths or roadways laid out in sections, each section displaying a plurality of spaces, a central portion having 105 a series of goals, a crossway leading from the starting points between the endmost spaces of the different sections comprising the roadway, said crossway having a series of spots of the same color as the nearest goal 110 to indicate the paths to be taken by moving objects to the endmost space of that one of the sections of the innermost path or roadway from which the moving object must be moved to enter the goal, and a revolute 115 portion at the center of the board provided with a gate whereby said revolute portion when turned may place the gate in position to uncover any goal.

4. A game apparatus comprising a board 120 presenting starting points differing in color, a series of concentric paths or roadways divided in sections, each section presenting a plurality of spaces, a series of central goals, one for each starting point, a crossway leading from each starting point through and crossing all said paths or roadways, each crossway having spots of the color corresponding with the color of the starting point, and a series of movable objects each provided 130

4
with means for indicating ownership of said movable object.

5. A game apparatus comprising a board presenting starting points differing in color, 5 a series of concentric paths or roadways divided in sections, each section presenting a plurality of spaces, a series of central goals, one for each starting point, a crossway leading from each starting point through and 10 crossing all said paths or roadways, each crossway having spots of the color corresponding with the color of the starting point,

a series of movable objects and a figure with a hoodoo, said movable objects and hoodoo each provided with means for indicating 15 ownership thereof.

In testimony whereof, I have signed my name to this specification, in the presence of two subscribing witnesses.
